UNITED STATES PATENT OFFICE.

GEORGE LOOMIS BROWNELL, OF WORCESTER, MASSACHUSETTS.

WINDING MECHANISM.

SPECIFICATION forming part of Letters Patent No. 621,484, dated March 21, 1899.

Application filed July 5, 1898. Serial No. 685,187. (No model.)

To all whom it may concern:

Be it known that I, GEORGE LOOMIS BROWNELL, a citizen of the United States, residing at Worcester, in the county of Worcester and 5 Commonwealth of Massachusetts, have invented new and useful Improvements in Winding Mechanisms, of which the following is a specification, accompanied by drawings forming a part of the same and representing 10 a winding mechanism embodying my invention.

My invention relates to that class of winding mechanisms which are usually employed in twine or cord twisting machines for the 15 purpose of winding the twisted cord upon a winding-spool and to traverse the cord from one end to the other of the spool, so that the cord will be laid uniformly thereon; and the object of my invention is to provide a winding 20 mechanism capable of being rotated at a high speed by reducing the friction and maintaining a perfect balance of the rotating parts, and I accomplish these objects by means of the mechanism hereinafter described, and shown 25 in the accompanying drawings, in which--

Figure 1 represents a portion of a twisting-machine, showing one of the flier-frames and winding-spools in side elevation. Fig. 2 represents a portion of the traversing ring provided with a groove or guideway for the traveler or cord-guide, said traversing ring being shown in transverse sectional view; and Fig. 3 represents a top view of the cord-guide or traveler removed from the traversing ring.

Similar letters refer to similar parts in the different figures.

The twisting-machine represented in Fig. 1 is of a usual and well-known type, comprising a rotating flier-frame consisting of the 40 upper and lower heads A and A', connected on diametrical sides of the flier-frame by a pair of rods B B', known as "flier-arms," said flier-frame being capable of rotation about a vertical axis by means of connected driving 45 mechanism. Held concentrically within the flier-frame is a winding-spool C, upon which the twisted cord is wound, and surrounding the flier-arms B B' is a ring D, attached to a bracket D', which is carried by the frame D'', capable of sliding vertically on a bar D³, which is attached to the framework of the machine 50 and provided with a rack D⁴, which engages

a pinion E, carried upon a shaft E', to which a reciprocating motion is imparted by means of a mangle-wheel F, attached to the shaft 55 E' and driven by a rotating star-wheel F', whereby a rising-and-falling motion is given to the frame D' and ring D equal in extent to the space between the upper and lower heads of the winding-spool C.

The traversing ring D is provided with an L-shaped groove G, opening upon the interior of the ring and adapted to receive a cord-guide or traveler H, preferably made of vulcanized fiber or similar material in order to 65 reduce its weight and consisting of a plate H', running in the horizontal section of the L-shaped groove G, and having a vertical flange H², running in the vertical section G' of the groove. The horizontal portion H' of 70 the traveler H projects beyond the inner surface of the traversing ring D and is provided with a notch I to receive one of the flier-arms B and with an eye J, through which the twisted cord a is conducted as it passes from 75 the twisting mechanism to the winding-spool. The cord-guide or traveler H is of sufficient length only to receive the notch I and the eye J, and during the operation of the machine it is driven around the traversing ring D with 80 great rapidity by the rotation of the flier-arm B, thereby winding the twisted cord around the winding-spool C, and during the rotation of the cord-guide in the groove of the traversing ring the cord is uniformly laid on the 85 winding-spool by the rising-and-falling motion of the ring D through its connected actuating mechanism.

I am aware that it is not new in winding mechanisms to provide a cord-guide capable 90 of rotating around the winding-spool in a grooved ring to which a traversing motion is imparted, and I do not herein claim such broadly. In winding mechanisms of this class, however, great difficulty is experienced 95 in preserving a proper balance of the rapidly-rotating parts and in reducing friction due to the pressure of the rapidly-rotating cord-guide upon the walls of its guideway. The friction of the cord-guide is increased by the 100 centrifugal force due to its weight and rapid rotation and also by the "pull" or strain exerted upon the cord-guide by the tension of the twisted cord. Owing to the difficulty of

properly lubricating the groove or guideway containing the cord-guide, it has been found necessary to adopt various expedients to reduce the friction upon the cord-guide, to maintain a perfect balance of the rapidly-rotating part, and to properly resist the pulling strain exerted by the cord as it passes through the eye of the cord-guide. These results have heretofore been accomplished by placing the eye of the cord-guide in a continuous rotating ring held within the groove of the traversing ring and also by constructing the cord-guide with a sleeve fitting one of the flier-arms. The former method necessitates the use of a large continuous metallic ring having an accurate fit throughout its entire contact with the traversing ring and of sufficient weight to render it rigid, with a large surface in contact with the guideway, and requiring constant lubrication to prevent its heating while running at a high rate of speed. The attachment of the cord-guide to a sleeve accurately fitting and capable of sliding on one of the flier-arms and having lugs engaging the annular groove in the traversing ring obviates some of the objections to a continuous rotating ring; but as the eye of the cord-guide must be located upon one side of the flier-arm inclosed by the sleeve the tension of the cord tends to rotate the sleeve upon the flier-arm, which requires a spline connection between the ring and flier-arm, thereby increasing the frictional surface in contact and the expense of construction. My present invention overcomes these several disadvantages by making the cord-guide as short as possible and of light material, such as vulcanized fiber, and resisting the tension or pull of the cord by means of a flange H^2 on the cord-guide, which is inclosed within the L-shaped slot of the traversing ring. The tension of the cord is also partially overcome by the centrifugal force exerted by the cord-guide, which tends to throw the cord-guide radially outward and

in opposition to the tension of the cord, which tends to draw the cord-guide radially inward. I thereby obviate the necessity of employing a continuous ring containing the cord-guide in order to counterbalance the opposite sides by causing the tension of the cord and the centrifugal force to counterbalance each other. The cord-guide is rapidly and cheaply made, is easily replaced when worn, and is capable of being rotated at a very high speed without lubrication of the guideway.

What I claim as my invention, and desire to secure by Letters Patent, is—

1. In a winding mechanism, the combination of a rotating flier-frame and a winding-spool held concentrically therein of a ring inclosing said frame and lying in a plane at right angles with its axis of rotation, said ring having on its inner side an L-shaped groove, actuating mechanism by which said grooved ring is given a reciprocating motion the length of the winding-spool, a traveler consisting of a short plate provided on its outer edge with a flange with its flanged edge inclosed in said L-shaped groove and having an eye or cord-guide with the inner edge of said traveler engaging said flier-frame, substantially as described.

2. The combination with a winding-spool and a flier-frame having an arm parallel with its axis of rotation, of a traversing ring provided with an L-shaped groove, means for imparting a traversing motion to said ring, a traveler consisting of a short plate with an eye or cord-guide and engaging said flier-arm and a flange on the outer edge of said plate and at right angles thereto, said flanged edge being inclosed in said L-shaped groove, substantially as described.

Dated this 29th day of June, 1898.
GEORGE LOOMIS BROWNELL.
